FIGURE 1 is a side elevational view of one embodiment of the lamp embodying my new design in the retracted position, the opposite side being a mirror image thereof;

FIG. 2 is a perspective view of the lamp of FIGURE 1 showing the lamp in an extended position;

FIG. 3 is a side elevational view of the lamp shown in FIG. 2;

FIG. 4 is a front elevational view of the lamp shown in FIG. 2;

FIG. 5 is a rear elevational view of the lamp shown in FIG. 2; and

FIG. 6 is a side elevational view of an alternative em-

bodiment of the lamp in the retracted state, which with respect to portions not shown is substantially the same as the embodiment of FIGURE 1.

The dominant features of my design reside in the portion shown in full lines.

I claim:

The ornamental design for a portable retractable lamp, substantially as shown and described.
